ICE CREAM CARTON

Morton H. Robinson, Devon, Pa., assignor to Container Corporation of America, Chicago, Ill., a corporation of Delaware

Filed Sept. 11, 1962, Ser. No. 71,653

Term of patent 14 years

(Cl. D58—12.6)

The FIGURE is a front perspective view of an ice cream carton, showing my design.

The side opposite that shown is substantially a mirror image of the side shown, while the rear and bottom walls are substantially plain and unornamented.

The essential feature of my design resides in the particular tear strip which is notched and shaped as shown.

I claim:

The ornamental design for an ice cream carton, as shown and described.
